BLOW ORGAN

Finn H. Magnus, Essex Fells, N. J.

Application September 5, 1952, Serial No. 308,015

1 Claim. (Cl. 84—360)

My invention relates to a blow organ and has as its principal object the provision of a novel and improved type of blow organ which can be operated by a gentle blowing action and without the necessity of a tiring effort on the part of an operator.

It is another object of my invention to provide a blow organ of the character described having a wind chest wherein air for operating the instrument may be accumulated under pressure, and having a baffle in the wind chest for controlling the flow of air from the wind chest to the reeds of the organ.

It is still another object of my invention to provide a blow organ of this type having parts which for the most part may be formed from an inexpensive plastic material, and which in accordance with my invention can be easily and quickly assembled into a complete unit.

Other objects and advantages of my invention will become apparent as the course of the specification progresses.

In accordance with my invention, I provide a wind chest wherein air for operating the instrument may be accumulated. The chest includes a plurality of openings and means are provided for selectively opening and closing such openings. A reed plate having a plurality of reeds thereon spaced for alignment with the openings in the chest is mounted in the chest so that the reeds are located at the interior ends of the openings, and a baffle is mounted opposite the reed plate in the chest to control the flow of air in the chest to the reeds as the openings in the chest are selectively opened by the aforesaid means. The baffle is of such a length that it is disposed opposite the reed plate for substantially the entire distance between end reeds of the plate; and preferably such baffle includes a plurality of individual cells for directing the air to the reeds which cells are open only at one end when the baffle occupies its assembled position.

I shall describe one form of my invention and then point out the novel features thereof in the claim.

In the accompanying drawings

Fig. 1 is a rear perspective view of a blow organ embodying the features of my invention;

Figure 2 is a longitudinal vertical sectional view taken on the plane of the line 2—2 of Fig. 1;

Figure 3 is a transverse vertical sectional view taken on the plane of the line 3—3 of Fig. 2;

Figure 4 is a view similar to Fig. 3 showing one of the keys depressed;

Figure 5 is a top longitudinal horizontal sectional view taken on the plane of the line 5—5 of Fig. 2;

Figure 6 is a bottom longitudinal horizontal sectional view taken on the plane of the line 6—6 of Fig. 2;

Figure 7 is a bottom plan view of the comb section;

Figure 8 is a top plan view of the reed plate;

Figure 9 is a bottom plan view of the baffle;

Figure 10 is a fragmentary top plan view of the gasket.

Referring to the drawings, reference character 1 designates a casing which simulates the form of a pipe

2

organ and is preferably formed from a suitable plastic material. Casing 1 encloses the wind chest 2 also preferably of a plastic material, the casing being adhesively secured to the edges of a plate 3 of which that portion 5 between integral flange portions 4 forms the bottom wall of the wind chest. Wind chest 2 also includes two half sections 5 and 6 adhesively secured to each other and to plate 3 along integral flange portions 4 which half sections form the front and back walls 7 and 8, and end walls 9 and 10 of the wind chest. The top wall of the wind chest comprises a comb section 11 which is provided with end and front and back flange portions 12 that overlap the top edges of the end, front and back walls of the wind chest. Such top edges are adhesively secured to the comb section.

Comb section 11 includes a plurality of transverse slots 20 spaced for alignment with a predetermined number of keys 21 forming the keyboard of the instrument. Secured to the underside of the comb section 11 in some suitable manner as by adhesive is a reed plate 22, preferably of a plastic material and having integral reeds 23 thereon which are aligned with slots 20 in comb section 11. Reed plate 22 may, for example, be of the type shown and described in applicant's Patent No. 2,373,129 issued April 10, 1945. Secured to the underside of the reed plate as by adhesive is a baffle 13 also preferably plastic and having walled channels or cells 24 which are aligned with the reeds 23 of reed plate 22. Channels 24 open out into the interior of wind chest 2 at only one end 26 at one edge of the baffle in spaced opposed relation to the wall 5 of the wind chest and serves to control the flow of air from the wind chest to the reeds.

The top side of comb section 11 has a suitable gasket 25 secured thereon having openings 30 aligned with slots 20 of comb section 11. Openings 30 and slots 20 of gasket 25 and comb section 11 respectively are covered by one end portion 31 of keys 21 in their normal position. Keys 21 are held in their covering position by springs 32 each of which has one end 33 locked under an overhanging lip 34 on comb section 11 and the other end pressed against end portion 31 of one of the keys. Keys 21 are pivoted intermediate their ends on the comb section and for this purpose are provided on their undersides with grooves 35 which mate with a projecting edge 36 on the comb. By depressing end portions 37 of keys 21 the keys may be pivoted against the bias of springs 32, thereby raising end portions 31 and uncovering openings 30 and slots 20.

Wind chest 2 is provided with an inlet 40 for air, and a flexible tube 41 fitted at one end over the inlet and having a mouth piece 42 at its other end. Tube 41 extends through an opening 43 in casing 1.

In operating the instrument air is blown through flexible tube 41 into wind chest 2 where it is accumulated under pressure. The keys are depressed in chosen sequence causing air in the wind chest to be forced through the channel in the wind chest aligned with a depressed key past the reed aligned with the depressed key and thence through the slot and opening in the comb and gasket respectively also aligned with such key to the outside of the chest. As the air rushes past the reed, the reed is caused to vibrate at a frequency determined by its length to produce the desired sound. The sound escapes from casing 1 through screened opening 50 in the rear wall. With the construction herein described only a gentle blowing action is required to operate the instrument, it being unnecessary to build the pressure up from atmospheric to playing pressure each time a key or combination of keys are depressed because of the reservoir of compressed air maintained in the wind chest. Furthermore, because of the baffle which directs the air

from the wind chest to the reeds, less air is required to play the instrument than would otherwise be required.

Although I have herein shown and described only one form of my invention, it is to be understood that various changes and modifications may be made therein within the scope of the appended claim without departing from the spirit and scope of my invention.

Having thus described my invention, what I claim is:

In a blow organ, the combination of a wind chest having a comb section as one wall thereof, the comb section having a plurality of openings therethrough, a reed plate including a plurality of reeds spaced for alignment of each reed with one of said openings, the reed plate being secured to the interior side of the comb section with the reeds located at the interior ends of said openings, a baffle secured to the reed plate inside said wind chest with one edge in opposed spaced relation to another wall of said wind chest, said baffle having a plurality of walled

wind cells each for one of said reeds of the reed plate, said wind cells being open at only one end through said edge of the baffle when the baffle is in its secured position, whereby air is permitted to flow from said wind chest into said cells only through the restricted space between said edge of the baffle and the second-mentioned wall of said wind chest.
